UNITED STATES PATENT OFFICE.

JOSEPH SCHMID, OF NEW ORLEANS, LOUISIANA.

RAILWAY-STATION INDICATOR.

SPECIFICATION forming part of Letters Patent No. 334,478, dated January 19, 1886.

Application filed April 25, 1885. Serial No. 163,477. (No model.)

To all whom it may concern:

Be it known that I, JOSEPH SCHMID, a citizen of the United States, and a resident of the city of New Orleans, parish of Orleans, and 5 State of Louisiana, have invented certain new and useful Improvements in Railway-Station Indicators; and I do hereby declare the following to be a full, clear, and correct description of the same, reference being had to the 10 annexed drawings, making a part of this specification.

This invention is especially intended as a street or station indicator for railway-cars; but it may be adapted for advertising purposes, 15 and applied to any kind of vehicles.

The invention consists in certain combinations and arrangements of parts, all of which are hereinafter fully described and specifically claimed.

20 On the drawings, Figure 1 is a front view of the indicator with the door of its casing partially open. Fig. 2 is a vertical section of the casing with side elevation of indicator. Fig. 3 is a vertical cross-section through the line $x-x'$ of Fig. 1; and Fig. 4 is a detailed view, partly 25 in section, of a shifting spur-wheel and adjacent parts.

A is a casing, of wood or other material, extending from the floor of the car to any desired height above same. Within this casing 30 is secured the main frame of the mechanism. This frame is composed of three parallel plates or bars, $b b' b''$, and connecting-rods $c c' c'' c''' c''''$.

The names or numbers of the streets or stations to be indicated are printed or otherwise 35 produced in separate lines across the face of a ribbon or tape, D, the opposite ends of which are attached to flanged drums E F, fitted on shafts $h i$, having journal-bearings in the 40 frame-plates $b b'$. The front edges of these plates are provided with caps $j j' k k'$, to permit of the introduction or removal of the shafts and drums as often as necessity may require. The aforesaid frame-plates $b b'$ are provided 45 at or about midway between the shafts $h i$ with projecting brackets $L L'$, having idlers or rollers $m m'$ journaled in the upper and lower outer corners thereof. Over these idlers or rollers the tape is made to operate so as to bring 50 the same in close proximity to a small glazed opening, N, made in the casing-door, through which the names on the tape are exposed to

view as they are successively brought in rear thereof. The aforesaid drums and tape are operated from the axle of the car through a 55 train of gearing, chain-wheels, and chains, as hereinafter described, the connection being made with the train of gearing through a cog-wheel, O, which is adapted to have a limited sliding movement on the squared or feathered 60 end of the drum-axle h . A spring, p, is interposed between the cog-wheel O and the adjacent frame-plate b' , for the purpose of pressing the said wheel outwardly, and thus causing its teeth to engage those of a pinion, q, forming 65 part of the train of gearing above alluded to.

R is a push-rod, which is supported in the same axial line as that of the drum-shaft h by the frame-plate b'' and a bracket, b''' , connected therewith. This rod is sufficiently long 70 to project through one side of the casing, and is adapted to have an endwise movement in its bearing, so that its inner end, which is recessed to fit the squared or feathered end of the shaft h , may be pressed on same, and thus 75 be made to throw the cog-wheel O out of gear. The inner end of this rod is provided with a collar, r, to limit its outward movement. The spring p, yielding to the pressure brought to bear against same, resumes its normal position and forces the cog-wheel O into gear again the moment pressure is removed therefrom.

The pinion q, from which motion is transmitted to the indicator through the cog-wheel O, is fitted on a shaft, q' , having bearings in 85 the frame-plates $b' b''$. This shaft is also provided with a cog-wheel, P, which is engaged by the pinion t of a shaft, t' , on which is also secured a chain-wheel, T, having a chain-connection, u, with the chain-wheel S of shaft t'' , 90 the journals of which operate in the lower ends of the frame-plates $b' b''$. This shaft is provided with a second chain-wheel, S', which is connected by an endless chain, v, with a chain-wheel, W, preferably made in two sections, as 95 shown in Figs. 2 and 3, so as to be secured to the car-axle w without having to remove either of the traction-wheels thereof.

To insure proper tension to the indicator-tape, as well as to cause the same to return to 100 its original position or starting-point, the axle i of the lower drum has one of its ends provided with a pinion, a, which is engaged by the cog-wheel a' of a shaft, a'' , likewise jour-

naled in the frame-plates *b b*, and having the inner end of a spring, B, connected therewith. The opposite end of this spring is secured to a stud, B', so that the said spring shall be 5 gradually tightened or "wound up" as the car moves forward. The relative proportions of the aforesaid pinion and cog-wheel should be such as to cause the spring to be wound up very gradually, and, if desired, intermediate 10 gear-wheels may be arranged to more effectually obtain this result. In like manner the number of wheels composing the "train of gearing" through which motion is transmitted to the indicator proper may be increased or diminished, as the length of the route to be traversed may render necessary. The opposite end of the drum-axle *i* is made 15 square, or otherwise adapted to receive a crank, (which can be inserted through a hole made in the side of the casing for said purpose,) to permit of a proper adjustment of the indicator, should same at any time be required.

The manner in which the tape is laid off and marked is as follows: The car or vehicle 20 provided with the apparatus is moved to the starting point of the route, and the mechanism adjusted so that the bulk of the tape shall be around the lower drum, and the tension-spring B perfectly free or unwound. The car is 25 then started, which imparts motion to the mechanism, and the tape connected therewith is then gradually drawn from the lower to the upper drum. As each street or station to be indicated is reached, that part of the tape 30 which has attained the elevation of the glazed opening N is marked, and this process is continued until the end of the route has been reached, or the round trip completed. The tape 35 is then removed, and the proper names printed or otherwise produced thereon over the aforesaid marks. When dry, the tape is replaced, and the mechanism being properly adjusted 40 the names will appear in their proper order as the points to be indicated along the route are 45 successively reached.

In the operation of the invention the backing of the car will not in any manner affect the working of the mechanism, as the latter will operate in either direction. Should it be

desired to start the car from any point other 50 than that first indicated on the tape, it is only necessary to throw the cog-wheel O out of gear by pressing inwardly the push-rod R, when the crank can be applied to the squared end of the drum-shaft *i*, and the tape readily 55 adjusted thereby.

In the application of my invention for long routes the said routes should be divided into sections, and each section should be provided with a tape properly laid off to indicate the 60 stations along same, and these tapes should be successively substituted for the preceding one as the end of each section is reached.

Instead of printing the names of streets or stations on the tapes, the latter may be made to 65 contain advertisements, and thus the indicator can be used as an advertising medium instead of as a street or station indicator.

Having described my invention, what I claim as new, and desire to secure by Letters Patent, 70 is—

1. The combination, with the frame-plates *b b'* and their connecting-rods, as described, the drum-axle *h*, having a squared or feathered end, and a cog-wheel adapted to fit said end 75 and have a sliding movement thereon, of the spring B and push-rod R, for causing the aforesaid wheel to engage with or be disconnected from an operating - pinion, substantially as 80 described and for the purpose set forth.

2. The combination of the shafts *h i*, provided with drums and tape, as described, the shaft *a'*, with spring B and cog-wheel *a'*, the latter adapted to engage a pinion on the shaft 85 *i*, as set forth, with the sliding cog-wheel O and spring *p*, fitted on the shaft *h*, the push-rod R, and the train of gearing, chains, and 90 chain-wheels, whereby the aforesaid mechanism is connected with the axle of a car, and thereby operated, substantially as and for the purpose specified.

In testimony whereof I affix my signature in presence of two witnesses.

JOSEPH SCHMID.
